FLUID PRESSURE MEDIUM DISPENSING
SYSTEMErnest A. Joerren, Brooklyn, N. Y., assignor to
Specialties Development Corporation, Bloom-
field, N. J., a corporation of New Jersey

Application March 4, 1944, Serial No. 525,122

7 Claims. (Cl. 62—1)

1

The present invention relates to fluid pressure medium dispensing systems, and more particularly to systems for dispensing liquid carbon dioxide having a relatively low temperature.

Liquid carbon dioxide generally is stored in metallic containers known as cylinders. When the cylinders are subjected to low temperatures, such as are encountered in artic regions or at high altitudes in the flight of aircraft on which the cylinders are used, the vapor pressure of the carbon dioxide within the cylinders is greatly lowered. Liquid carbon dioxide is also stored in large capacity containers wherein it is maintained at low temperature and a correspondingly low vapor pressure. For example, where the liquid carbon dioxide is maintained at or is subjected to a temperature of about -40° F. the vapor pressure thereof is about 131 pounds per square inch (gauge).

It has been found that at such low temperatures, the correspondingly low pressure of the carbon dioxide in the containers will not effect rapid discharge of the liquid carbon dioxide therefrom. This is disadvantageous, particularly in cases where the carbon dioxide is used for fire extinguishing purposes. In extinguishing fires, it is desirable to direct a large quantity of carbon dioxide to the location of the fire in a minimum period of time.

The present invention aims to overcome the foregoing difficulties and disadvantages encountered in discharging liquid carbon dioxide having a relatively low temperature, by introducing a gaseous medium having a substantial pressure into the containers at or about the time the carbon dioxide is to be discharged, whereby the pressure in the containers is substantially increased to facilitate rapid and effective discharge. The invention further contemplates utilizing the gaseous pressure medium for operating discharge control means, such as a valve, associated with the containers.

An object of the present invention is to provide a fluid pressure medium dispensing system adapted to overcome the foregoing difficulties and disadvantages.

Another object is to provide a system, wherein liquid carbon dioxide at low temperature and correspondingly low pressure is subjected to a higher pressure adapted to facilitate rapid and effective discharge thereof.

Another object is to provide a system of the foregoing character wherein an auxiliary source of gaseous pressure medium is utilized to effect

discharge of liquid carbon dioxide stored in one or more containers.

Another object is to provide a system, wherein the gaseous medium is also utilized to effect operation of valves and the like for releasing the carbon dioxide.

Another object is to discharge liquid carbon dioxide from a container at a uniform predetermined rate over a wide range of temperatures.

10 A further object is to provide a system of the foregoing character which is simple and economical in construction and positive in operation.

Other and further objects of the invention will be obvious upon an understanding of the illustrative embodiment about to be described, or will be indicated in the appended claims, and various advantages not referred to herein will occur to one skilled in the art upon employment of the invention in practice.

20 Preferred embodiments of the invention have been chosen for purposes of illustration and description and are shown in the accompanying drawing, forming a part of the specification, wherein:

25 Figure 1 is a diagrammatic view, partly in section, of a system illustrating an embodiment of the invention, wherein liquid carbon dioxide is stored in a plurality of containers.

Figure 2 is a diagrammatic view, partly in section, of a system illustrating another embodiment of the invention, wherein liquid carbon dioxide is stored at low temperatures in an insulated container.

30 Referring more particularly to Figure 1 of the drawing, there is shown a system comprising one or any suitable number of containers 10, of which two are shown for illustrative purposes. The containers 10 may be metallic cylinders of standard construction and adapted to contain liquid carbon dioxide at relatively high internal pressure, and each cylinder may be equipped with a suitable release device 11 about to be described.

40 Each cylinder 10 is also equipped with the usual syphon tube 12 for withdrawing liquid carbon dioxide from the lower end of the cylinder and has its upper end secured to the release device 11, herein shown diagrammatically. Since the cylinders and release devices shown herein are substantially identical in construction, a description of one cylinder and its release device will suffice.

45 In practice, the release device 11 may comprise a valve casing or housing having an inlet chamber 14 in communication with the syphon tube and an outlet chamber 15 having a discharge

conduit 16 connected thereto which is adapted to direct the carbon dioxide to its point of use. Intermediate the inlet and outlet chambers, an opening is provided with a valve seat for receiving a suitable valve disc or member 17 serving as a discharge control means.

The valve member is adapted to be sealed against the valve seat by the pressure of the carbon dioxide in the container, or by a spring or the like (not shown). The valve member 17 is adapted to be unseated by fluid pressure operable means such as a piston 19 disposed in a piston chamber 20 separated from the outlet chamber by a partition 21. The valve member 17 and piston 19 are operatively connected by a rod 22 extending through an aperture in the partition 21.

The container is further provided with means for introducing a gaseous pressure medium into the vapor space, which may comprise a suitable inlet valve including a member 24 adapted to be seated against and seal an inlet port by the pressure of the carbon dioxide in the container or by spring means (not shown). Since the present invention is not concerned with the specific type of valve to be utilized, a detailed description thereof is believed to be unnecessary.

The gaseous pressure medium is supplied from a suitable source 30 by a conduit 31 having a suitable control valve 32 therein; and a branch conduit 34 leading to the inlet valve. The gaseous pressure medium is also adapted to effect operation of the fluid pressure operable piston 19, and, to accomplish this, the conduit 31 or the branch conduit 34 is connected by a conduit 33 to the piston chamber 20. If desired a thermo-responsive pressure regulating valve 35 of suitable design may be connected in the conduit 31, the purpose of which will be described hereinafter.

The source of gaseous pressure medium 30 may be a container in which is stored a compressed or liquefied gas having a much higher pressure than carbon dioxide at a relatively low temperature. Such gases may be air, argon, carbon monoxide, helium, hydrogen, krypton, neon, nitrogen, and oxygen or mixtures of any of these gases. Preferably, nitrogen or compressed air is utilized because of their comparative low cost and general availability.

Carbon dioxide may also be utilized, provided it is maintained at temperatures at which it has a relatively high vapor pressure. To accomplish this, the source 30 may be heated in any suitable manner.

Referring now to Figure 2, there is shown a heat insulated container 10' of the bulk storage type for storing a large volume of liquid carbon dioxide which may be used for fire extinguishing purposes and is maintained at relatively low temperatures by means of a refrigerating coil 36 extending through the container, or by other suitable means.

The container has an outlet at its bottom normally closed by a valve member 17', constituting discharge controlling means, the valve member being adapted to be unseated by fluid pressure operable means, such as a piston 19' disposed in a piston chamber 20' and operatively connected to the valve member 17' by a rod 22' extending through a partition 21'. The outlet is adapted to be placed in communication with a discharge conduit 16' when the valve member 17' is unseated.

An inlet valve, illustrated as a valve member 24', is provided at the top of container 10' for introducing a gaseous pressure medium into the

vapor space of the container from a source 30 by means of a conduit 31'. The fluid pressure operable piston 19' is connected for operation by the gaseous pressure medium from the source 30 by means of a branch conduit 34' leading from the conduit 31' to the piston chamber 20'.

Insofar as the present invention is concerned, the systems illustrated in Figures 1 and 2, respectively, do not differ essentially. The system shown in Figure 1 is designed for storing and discharging liquid carbon dioxide which may be subjected to low temperature and resulting in ineffective discharge by being exposed to natural elements, while the system shown in Figure 2 is designed to overcome ineffective discharge in cases where the liquid carbon dioxide is stored and maintained at low temperatures by refrigerating means to accomplish other advantages, such as low pressure storage and increased snow forming ability. Thus, for the purpose of providing rapid and effective discharge at low temperature, the condition of the liquid carbon dioxide may be assumed to be the same in both systems.

For example, it is contemplated to discharge liquid carbon dioxide at temperatures between about 20° F. and the triple point of carbon dioxide, namely -69.88° F. At such temperatures, the vapor pressure of the stored carbon dioxide is relatively low as compared with the vapor pressure of carbon dioxide at normal atmospheric temperature, for example, at about 70° F. Consequently, the discharge rate of the carbon dioxide is substantially lower and the time required to discharge a given amount of carbon dioxide will be materially greater. By way of example, the vapor pressure of liquid carbon dioxide at various temperatures within the contemplated range and at normal atmospheric temperature is as follows:

Temperature, Degrees F.	Vapor Pressure, Lbs./sq. In. (gauge)
70	838
45	407
20	290
0	200
-20	131
-40	80
-60	64
-68	

In practicing the present invention, the pressure of the gaseous medium at the source 30 is such that, when it is introduced into the containers 10 or 10', the resulting pressure in the vapor space of the containers will be between about 300 and about 1000 pounds per square inch. Preferably, the pressure established in the vapor space is in the neighborhood of 500 pounds per square inch, which pressure provides for rapid and effective discharge of the carbon dioxide. It will be understood that any pressure below the safe working pressure of the containers may be established therein. For example, where the container is a high pressure steel cylinder (Figure 1), pressures up to about 3000 pounds per square inch may be established to discharge the carbon dioxide, while where the container is a low pressure bulk storage tank (Figure 2), a pressure of about 500 pounds per square inch may be safely established without damaging the container.

In connection with the system shown in Figure 1, where the temperature of the carbon dioxide may vary over a wide range, it is desirable to regulate the pressure which is established within

the container so that it is substantially uniform, regardless of whether the temperature is -40° or 20° F., for example. Thus, where it is desired to establish a discharge pressure of about 500 pounds per square inch, the thermo-responsive pressure regulating valve 35 is adjusted to introduce the gaseous medium at pressures adapted to establish such discharge pressure in the container at any temperature within the range the carbon dioxide may have. Consequently, the 10 carbon dioxide can be discharged as rapidly and effectively at -60° F., for example, as it can be discharged at 20° F.

In connection with the system shown in Figure 2, the temperature of the carbon dioxide, preferably, is maintained constant, and the gaseous pressure medium is supplied at a constant pressure to provide a predetermined discharge rate.

In operation of the systems shown in Figures 1 and 2, the control valve 32 is operated manually or automatically, either locally or remotely, to release the gaseous pressure medium from the source 38. The gaseous pressure medium is directed to the piston chamber 28 or 28' to operate the piston 19 or 19' and unseat the valve member 17 or 17', to thereby place the system in condition for discharge of the carbon dioxide through the discharge conduit 16 or 16'. Substantially simultaneously with the operation of the valve member 17 or 17', the gaseous pressure medium is introduced into the vapor space of the container to establish the desired discharge pressure which expels the liquid carbon dioxide from the container.

From the foregoing description, it will be seen that the present invention provides systems for rapidly and effectively discharging liquid carbon dioxide having relatively low temperatures by utilizing an auxiliary gaseous pressure medium at a high pressure and stored in a separate container. Uniform predetermined discharge pressures are adapted to be established thus providing a high predetermined rate of discharge of the carbon dioxide at low temperatures.

The systems in accordance with the present invention are simple and economical to manufacture and are readily operated to accomplish the advantages described herein.

As various changes may be made in the form, construction and arrangement of the parts herein, without departing from the spirit and scope of the invention and without sacrificing any of its advantages, it is to be understood that all matter herein is to be interpreted as illustrative and not in any limiting sense.

It is also to be understood that the following claims are intended to cover all the generic and specific features of the invention herein described, and all statements of the scope of the invention which, as a matter of language, might be said to fall therebetween.

I claim:

1. In a fluid pressure medium dispensing system wherein liquid carbon dioxide is stored, the combination of a container for storing the liquid carbon dioxide having an inlet and outlet means in fluid flow communication with the lower interior part of said container, a pressure medium operable valve for controlling the discharge of carbon dioxide through said outlet means, a source of high pressure fluid medium in gaseous form, and means for conducting the medium to said valve to operate the same and for conducting the medium to said inlet to introduce the medium into said container, whereby the valve is condi-

tioned to permit discharge of carbon dioxide through said outlet means and the carbon dioxide in said container is subjected to a higher pressure than its own to expel the same therefrom at a more rapid rate.

5 2. In a fluid pressure medium dispensing system wherein liquid carbon dioxide is stored, the combination of a container for storing the liquid carbon dioxide having an inlet and outlet means in fluid flow communication with the lower interior part of said container, a pressure medium operable valve for controlling the discharge of carbon dioxide through said outlet means, a source of high pressure gaseous medium, means

15 for conducting the medium to said valve to operate the same and for conducting the medium to said inlet to introduce the medium into said container, whereby the valve is conditioned to permit discharge of carbon dioxide through said outlet means and the carbon dioxide in said container is subjected to a higher pressure than its own to expel the same therefrom at a more rapid rate, and thermo-responsive pressure regulating means in said conducting means.

20 3. In a fluid pressure medium dispensing system wherein liquid carbon dioxide is stored, the combination of a plurality of containers for storing the liquid carbon dioxide each having an inlet and outlet means in fluid flow communication with the lower interior part of said container, pressure medium operable valves, one being provided for each outlet means to control the discharge of carbon dioxide therethrough, a source of high pressure gaseous medium, and means for 25 conducting the medium to each valve to operate the same and for conducting the medium to said each inlet to introduce the medium into said containers, whereby the valves are conditioned to permit discharge of carbon dioxide through 30 said outlet means and the carbon dioxide in said containers is subjected to a higher pressure than its own to expel the same therefrom at a more rapid rate.

35 4. In a fluid pressure medium dispensing system wherein liquid carbon dioxide is stored, the combination of a plurality of containers for storing the liquid carbon dioxide each having an inlet and outlet means in fluid flow communication with the lower interior part of said container,

50 pressure medium operable valves, one being provided for each outlet means to control the discharge of carbon dioxide therethrough, a source of high pressure gaseous medium, means for conducting the medium to each valve to operate the same and for conducting the medium to said each inlet to introduce the medium into said containers, whereby the valves are conditioned to permit discharge of carbon dioxide through said outlet means and the carbon dioxide in said containers is subjected to a higher pressure than its own to expel the same therefrom at a more rapid rate, and thermo-responsive pressure regulating means in said conducting means.

55 5. In a fluid pressure medium dispensing system wherein liquid carbon dioxide is stored, the combination of an insulated container for storing the liquid carbon dioxide having an inlet and outlet means in fluid flow communication with the lower interior part of said container, refrigerating means for maintaining the carbon dioxide at a below normal atmospheric temperature and its corresponding pressure, a pressure medium operable valve for controlling the discharge of carbon dioxide through said outlet means, a source of high pressure gaseous medium, and means for

conducting the medium to said valve to operate the same and for conducting the medium to said inlet to introduce the medium into said container, whereby the valve is conditioned to permit discharge of carbon dioxide through said outlet means and the carbon dioxide in said container is subjected to a higher pressure than its own to expel the same therefrom at a more rapid rate.

6. In a fluid pressure medium dispensing system wherein liquid carbon dioxide is stored, the combination of a container for storing the liquid carbon dioxide having an inlet and outlet means in fluid flow communication with the lower interior part of said container, a pressure medium operable valve for controlling the discharge of carbon dioxide through said outlet means, a source of high pressure gaseous medium, means for conducting the medium to said valve to operate the same and for conducting the medium to said inlet to introduce the medium into said container, whereby the valve is conditioned to permit discharge of carbon dioxide through said outlet means and the carbon dioxide in said container is subjected to a higher pressure than its own to expel the same therefrom at a more rapid rate, and a check valve in said inlet maintained in closed position by the pressure of the carbon dioxide in said container and adapted to be opened by the pressure of the high pressure gaseous medium.

7. In a fluid pressure medium dispensing sys-

tem wherein liquid carbon dioxide is stored, the combination of a container for storing the liquid carbon dioxide having an inlet and outlet means in fluid flow communication with the lower interior part of said container, a normally closed valve for controlling the discharge of carbon dioxide through said outlet means, pressure medium actuated means for controlling the operation of said valve, a source of high pressure fluid medium in gaseous form, and means for conducting the medium to said pressure actuated means to operate the same and for conducting the medium to said inlet to introduce the medium into said container, whereby the valve is conditioned to permit discharge of carbon dioxide through said outlet means and the carbon dioxide in said container is subject to a higher pressure than its own to expel the same therefrom at a more rapid rate.
